COMBINED MOLD AND PERMANENT OUTSIDE SHELL FOR EXTERIOR LIGHTING FIXTURE

Howard W. Stentz, 6956 Delmeta Lane,
Dallas, Tex. 75240

Filed July 19, 1973, Ser. No. 380,887

Term of patent 14 years

Int. Cl. D26—03

U.S. Cl. D48—31

FIG. 1.

FIG. 2.

FIG. 3.

FIG. 4.

FIG. 5.

FIG. 6.

FIG. 1 is a perspective view of a combined mold and permanent outer shell for exterior lighting fixture showing my new design;

FIG. 2, a front elevation view thereof;

FIG. 3, a side elevation view thereof;

FIG. 4, a rear elevation view thereof;

FIG. 5, a top plan view thereof; and

FIG. 6, a bottom plan view thereof.

I claim:

The ornamental design for a combined mold and permanent outside shell for exterior lighting fixture, substantially as shown.
